UNITED STATES PATENT OFFICE.

ALBERT W. PEARSALL, OF LOWELL, MASSACHUSETTS, ASSIGNOR TO THE LAMSON COMPANY, OF NEWARK, NEW JERSEY, A CORPORATION OF NEW JERSEY.

PNEUMATIC-DESPATCH-TUBE APPARATUS.

1,075,790.

Specification of Letters Patent.

Patented Oct. 14, 1913.

Application filed May 5, 1908. Serial No. 430,958.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

My invention relates to improvements in pneumatic despatch tube apparatus and particularly to a shifting current or combination vacuum all sealed system.

The object of this invention is to provide means for shifting the air current from one outgoing line or circuit of tubing to another, maintaining a normally sealed air circuit as in an independent type of apparatus or regular tube line, and to provide a means of single control for a plurality of lines.

In the accompanying drawings is illustrated a form of construction embodying my invention in which:—

Figure 1 is a diagrammatic view of a pneumatic despatch tube system showing the controlling mechanism in operating connection therewith. Fig. 2 is an enlarged side elevation of the despatching inlets at the cashier's or central station. Fig. 3 is a front elevation of Fig. 2. Fig. 4 is an enlarged sectional view of one of the upward despatching inlets at the cashier's station. Fig. 5 is a side elevation partly in section of a downward despatching inlet. Fig. 6 is a front elevation enlarged of the air inlet timing and controlling mechanism. Fig. 7 is a plan view of Fig. 6. Fig. 8 is a sectional view on line 8—8 Fig. 6, and Fig. 9 is sectional view on line 9—9 Fig. 6 looking in the direction indicated by arrows.

Like letters of reference refer to like parts throughout the several views.

Referring to Fig. 1, C represents the cashier's or central station and S' and S² represent sales or sub-stations. 1 is a tube for the transmission of carriers from central station C to sub-station S' and 2 is a tube for the transmission of carriers from the central station C to sub-station S² said tube 2 being connected with and in communication with the tube 1 through apertures 6, 45 chamber 5 and apertures 4. 3 is a tube for transmitting carriers from sub-stations S' and S² to the central station C and which tube is connected with the tube 2 at sub-station S² through apertures 7, chamber 8 and 55 apertures 9. The transit tube 3 at central

station C is connected with the usual delivery terminal 10 which terminal is connected with the usual vacuum drum 12 by a tube 11. 13 is an air inlet tube connected with the transit tubes 1 and 2 at the central station C and adapted to be controlled by the normally closed valve 14 to admit air to said tubes for driving carriers. 15 and 16 are despatching inlets at the central station C for despatching carriers in the transit tubes 1 and 2 respectively and 17 and 18 are the respective delivery terminals for said tubes controlled by the usual valves 19 and 20. 21 and 22 are ordinary despatching inlets located at sub-stations S² and S' respectively 70 for inserting carriers into the tube 3 for transmission.

Mounted in the cylinder 23 is a piston 24 carrying on the upper end thereof an arm 25 to the outer end of which arm is secured 75 the air inlet valve 14. Connecting the cylinder 23 above the piston 24 with the vacuum tube 11 is a passage 26 and connecting said cylinder 23 beneath said piston with the vacuum tube 11 is a passage or by-pass 27 80 controlled by an adjustable timing valve 28 and adapted to normally balance the vacuum on both sides of piston 24 allowing said piston to remain at the bottom of the cylinder 23 and holding the air inlet valve 14 closed. 85 28^a is a passage adapted to admit air to cylinder 23 beneath piston 24 and is controlled by the normally closed valve 29 attached to the lower end of the lever 30 and which lever is pivoted at 31 and carries an 90 arm 32 with an adjustable weight 32^a mounted thereon.

33 is a diaphragm mounted in casing 34 and carries attached thereto the stem 35 the outer end of said stem being pivoted at 36 95 to lever 30. This diaphragm 33 is open to the atmosphere on the outer side, the inner side being inclosed by the casing 34 which is connected with and in communication with the tube 13.

The despatching inlets 15 and 16 at central station C are similar in construction, the inlet 15 being in communication with the tube 13 and the inlet 16 in communication with said tube 13 through a branch air tube 2^a. 105 37 is an outer or manually operated valve pivoted at 38 to casing or inlet 15 and 39 is an inner or automatic valve pivoted at 40 and adapted to control the passage of air through the tube 1. The inlet 16 is con- 110

trolled by a similar outer valve 37^a pivoted at 38^a and a like inner or automatic valve 16^a pivoted at 40^a. 41 is a shaft pivoted in and common to both inlets 15 and 16 and carries the pawls 42 and 42^a adapted to co-operate with latches 43 and 43^a respectively on valves 39 and 39^a to retain one or the other of said valves open. 44 is a spring mounted on shaft 41 and adapted to hold 10 said pawls in position to retain one of the latches 43 or 43^a. 45 is an arm fixed to the shaft or pivot 38, said arm being pivoted at 46 to a link 47 having a slot 48 in its outer end. 50 is an arm fixed to the shaft or pivot 15 40 and carrying a pin or stud 51 mounted in slot 48.

Fixed to the shaft or pivot 38^a is an arm 45^a pivoted at 46^a to a link 47^a having a slot 48^a in its outer end and in which slot is 20 mounted a stud or pin 51^a carried on the outer end of an arm 50^a fixed to the shaft or pivot 40^a.

The mechanism shown in Fig. 5 is identical with that in Fig. 4 the inlet being so arranged that carriers may be despatched from the central station downward instead of upward.

In the normal position of the apparatus one of the valves 39 or 39^a is always open 30 thereby permitting a circuit of air to be established when the valve 14 is automatically opened upon the despatching of a carrier. In Figs. 2 and 3 the valve 39^a is shown open being retained by the pawl 49^a thereby leaving the transmission tube 2 in communication with the air inlet tube 13.

To despatch a carrier from station C to sub-station S² the operator opens the valve 37^a which through arm 45^a causes the link 40 47^a through slot 48^a to ride on pin 51^a without engaging the trip 49^a secured to the shaft 41 and releasing the valve 39^a which is already open (see Figs. 2 and 3).

The carrier is now inserted in the inlet 16 45 and the valve 37^a closed. In the meantime the opening of said valve 37^a destroys the vacuum in tubes 2^a and 13 and diaphragm casing 34 releasing the diaphragm 33 which acting through lever 30 opens valve 29 admitting air through passage 28 and destroying the vacuum in the cylinder 23 beneath piston 24. The vacuum maintained above piston 24 permits the atmospheric pressure beneath to raise said piston 24 and through 50 arm 25 open valve 14 thereby admitting through tube 13 and branch tube 2^a atmospheric pressure for driving the carrier through the tube 2 toward the sub-station S². The closing of the valve 37^a has increased the vacuum in tube 13 and casing 34 55 sufficiently to move the diaphragm 33 inward and through stem 35 and lever 36 has closed valve 29 cutting off the admission of air to the cylinder 23 beneath the piston 24 60 which piston gradually drops by gravity on

account of the air beneath being gradually exhausted through by-pass 27 into the vacuum tube 11. The exhaust of air through this by-pass is timed by the adjustable valve 28 so that by the time the carrier has delivered at sub-station S² the valve 14 has closed cutting off the admission of air to the system.

In despatching a carrier from the central station C to the sub-station S', the operator 70 opens the valve 37 which acts through arm 45 and link 47 to engage the trip 49 and move the pawl 42^a thereby releasing the latch 43^a and allowing the valve 39^a to close cutting off the portion of the transmission tube 2 between the sub-station S' and central station C from communication with the air inlet tube 13. In the meantime the pin 51 is engaged by the end of slot 48 and through arm 50 opens the valve 39 when the carrier is inserted into the inlet 15. The valve 37 is now closed leaving valve 39 open being retained by the pawl 42. The diaphragm 33 has been released in the manner heretofore described and the valve 14 80 opened admitting air and driving the carrier through tube 1 toward the sub-station S', the valve 14 closing and cutting off the admission of air by the time the carrier has delivered at said station.

In returning a carrier from sub-station S' or S² the carrier is inserted into either inlet 21 or 22 causing the valve 14 to open in the manner described admitting air to the inlet tube 13 which traveling through either the tube 1 or the tube 2, according to which valve 39 or 39^a is open, enters the tube 3 through apertures 7 driving the carrier to the central station C, the valve 14 closing when said carrier delivers at said station.

Having thus described my invention and set forth a construction embodying the same, what I claim as new and desire to secure by Letters Patent of the United States is,—

1. In a pneumatic despatch tube apparatus, a plurality of despatching and receiving stations, a plurality of normally closed transit tubes connecting said stations, means for exhausting the air from said transit tubes, a normally closed air inlet adapted to admit air to said tubes for driving carriers, and means for automatically controlling the admission of air through said inlet and means for switching said air to create a flow of the same through any of said transit tubes for driving carriers between any of said stations.

2. In a pneumatic despatch tube apparatus, a plurality of despatching and receiving stations, a plurality of normally closed transit tubes connecting said stations, means for exhausting the air from said transit tubes, a normally closed air inlet adapted to admit air to said tubes for driving carriers, means for automatically con- 130

trolling the admission of air through said inlet and means for switching said air to create a flow of the same through any of said transit tubes for driving carriers between any of said stations, and means for 5 automatically closing said inlet and cutting off the flow of air when there are no carriers in transit in said tubes.

3. In a pneumatic despatch tube apparatus, a central station, a plurality of sub-stations, an independent normally closed transit tube connecting each of said sub-stations with said central station for selectively transmitting carriers from said central station to the required sub-station, a 10 normally closed return tube connecting said sub-stations with said central station for the transmission of carriers from any of said sub-stations to said central station, connections between said transit tubes and said return tube, means for normally maintaining a vacuum in all of said tubes, a normally closed air inlet adapted to admit air to said tubes for driving carriers, and means for 15 automatically controlling the admission of air through said inlet and for switching the flow of air through any of said transit tubes for the transmission of carriers between said central station and any of said sub-stations.

4. In a pneumatic despatch tube apparatus, a central station, a plurality of sub-stations, an independent normally closed transmission tube connecting each of said sub-stations with said central station for selectively transmitting carriers from said central station to the required sub-station, a 20 normally closed return tube connecting said sub-stations with said central station for the transmission of carriers from any of said sub-stations to said central station, connections between said transmission tubes and said return tube, means for normally maintaining a vacuum in all of said tubes, a normally closed air inlet adapted to admit air 25 to said tubes for driving carriers, means for automatically controlling the admission of air through said inlet and for switching the flow of air through any of said transit tubes for the transmission of carriers between said central station and any of said sub-stations, and means for timing the admission of air to the interval necessary for the transmission of the carriers.

5. In a pneumatic despatch tube apparatus, a plurality of despatching and receiving stations, a plurality of normally closed transit tubes connecting said stations, means for normally maintaining a vacuum in said transit tubes, a normally closed air inlet 55 adapted to admit air to said tubes for driving carriers, and air-controlling means, a portion of which is adapted to be automatically operated by a fluctuation of said vacuum to admit air through said inlet and a portion of which is adapted to switch the

so admitted air to any of said transit tubes for transmitting carriers between any of said stations and means located on each of said transit tubes for creating a fluctuation in said vacuum.

70

6. In a pneumatic despatch tube apparatus, a plurality of despatching and receiving stations, a plurality of normally closed transit tubes connecting said stations, means for normally maintaining a vacuum in said transit tubes, a normally closed air inlet adapted to admit air to said tubes for driving carriers, air-controlling means, a portion of which is adapted to be automatically operated upon a fluctuation of said vacuum to admit air through said inlet and another portion of which is adapted to switch the so admitted air to any of said transit tubes for transmitting carriers between any of said stations, and means for timing the admission of air to the interval necessary for the transmission of the carriers and means located on each of said transit tubes for creating a fluctuation in said vacuum for actuating said switching portion of said air controlling means.

75

7. In a pneumatic despatch tube apparatus, a plurality of transmission tubes each provided with an inlet orifice, a movable closure for each of said orifices, an air inlet adapted to admit air to said tubes for driving carriers, and means for automatically controlling the admission of air through said inlet and for shunting the flow of air therefrom through the tube the closure of which has been last actuated.

80

8. In a pneumatic despatch tube apparatus, a plurality of despatching and receiving stations, a plurality of normally closed transit tubes connecting said stations, means for exhausting the air from said transit tubes, a normally closed air inlet adapted to admit air to said tubes for driving carriers, means for controlling the admission of air through said inlet, and means, the parts of which are operatively interconnected, for shunting said air to create a flow of the same through any desired transit tube for driving carriers between stations.

85

9. In a pneumatic despatch tube apparatus, a plurality of transmission tubes each provided with an inlet orifice, a closure for each of said orifices, means for admitting air to said tubes when said orifices are closed, and an air directing device, co-acting with said closures for shunting air from said admitting means for the same into one or another of said tubes, according to which of said closures has been last opened, said device being common to said plurality of tubes.

90

10. In a pneumatic despatch tube apparatus, a plurality of transmission tubes each provided with an inlet orifice, a closure for each of said orifices, means for admitting

95

100

105

110

115

120

125

130

air to said tubes when said orifices are closed, a device, co-acting with said closure for shunting air from said admitting means for the same into one or another of said tubes, according to which of said closures has been last opened, and means for controlling the flow of air through said admitting means.

11. In a pneumatic despatch tube apparatus, a plurality of transmission tubes each provided with an inlet orifice, a closure for each of said orifices, means for admitting air to said tubes when said orifices are closed, a device, co-acting with said closure for shunting air from said admitting means for the same into one or another of said tubes, according to which of said closures has been last opened, and automatic means for controlling the flow of air through said admitting means.

12. In a pneumatic despatch tube apparatus, a plurality of transmission tubes each provided with an inlet orifice, a closure for each of said orifices, means for admitting air to said tubes when said orifices are closed, a device, co-acting with said closure for shunting air from said admitting means for the same into one or another of said tubes, according to which of said closures has been last opened, and automatic time element means for controlling the flow of air through said admitting means.

13. In a pneumatic despatch tube apparatus a plurality of transmission tubes each

provided with an inlet orifice, a movable closure for each of said orifices, an air inlet adapted to admit air to said tubes for driving carriers, and means for automatically controlling the admission of air through said inlet by a variation in pressure in a part of said apparatus and for shunting the flow of air from said inlet through the tube the closure of which has been last actuated, said actuation of said closure normally developing the variation in pressure capable of rendering operative said automatic controlling means, for the purpose aforesaid.

14. In a pneumatic despatch tube apparatus a plurality of transmission tubes each provided with an inlet orifice, a closure for each of said orifices, means for admitting air to said tubes when said orifices are closed, a device, co-acting with said closure for directing air from said admitting means for the same into one or another of said tubes and away from a tube into which it has previously been free to flow, according to which of said closures has been last opened, and means for controlling the flow of air through said admitting means.

In testimony whereof, I have signed my name to this specification in the presence of two subscribing witnesses, this 1st day of May A. D. 1908.

ALBERT W. PEARSALL.
